UNITED STATES PATENT OFFICE

2,522,765

BATH DEVICE HAVING A NONSKID
FLOOR SURFACE

Albert C. Sandberg, La Fayette, Ind.

Application January 29, 1947, Serial No. 724,973

6 Claims. (Cl. 4—173)

1

My invention relates to the production of a non-skid surface on the bottoms of bath tubs, on the floors of shower baths, and on other sloping surfaces which are contacted by the bare human foot when wet. For simplicity of description, I shall describe my invention hereinafter as embodied in a bath tub; but it is to be understood that the invention has applications elsewhere than in a bath tub.

It is the object of my invention to provide in a bath tub at bottom surface so formed as to reduce greatly the possibility of slipping. Another object of my invention is to provide on the bottom of a bath tub a multiplicity of bosses which will be so shaped and arranged as to create a minimum of interference with drainage of water from the tub. Still another object of my invention is to provide on the bottom of a bath tub a multiplicity of bosses which, while effective to prevent slipping, will not result in discomfort to a user of the tub.

In carrying out my invention, I form on the tub bottom a multiplicity of bosses of definite shape and arranged in a definite pattern with respect to each other and to the direction of water-flow over the bottom of the tub as it is emptied. The bosses, in the preferred embodiment of the invention, are generally oval in plan, but with one end larger than the other, the length of the ovals being approximately twice or somewhat more than twice their maximum width. The sides of the ovals are differently shaped, one side being relatively straight while the other is relatively curved. The bosses are arranged on the tub-bottom in longitudinal and transverse rows, the longitudinal rows being substantially parallel to the center-line of the tub and the transverse rows coinciding approximately with the contour lines of the tub-bottom. The bosses are individually oriented with their major axis at an angle of approximately 45° to the longitudinal center-line of the tub and with their smaller ends and straighter edges on their upstream sides.

The accompanying drawing illustrates my invention: Fig. 1 is a plan view and Fig. 2 a side elevation of a bath tub of common form in which my invention has been embodied; Fig. 3 is a transverse vertical section through the tub shown in Figs. 1 and 2; Fig. 4 is a fragmental plan view of the tub-bottom on an enlarged scale; and Figs. 5 and 6 are fragmental vertical sections on lines 5—5 and 6—6, respectively, of Fig. 4.

The bath tub 10 shown in Figs. 1, 2, and 3 is of common form, the bottom 11 of the tub sloping

2

transversely toward the longitudinal center-line and sloping longitudinally toward a waste-opening 12 at one end of the tub. The non-skid surface of the tub-bottom 11 is provided by a multiplicity of bosses each designated in its entirety by the reference numeral 15, such bosses being of a definite form and arranged in a definite manner, both to be hereinafter described.

As will be clear from Fig. 4, each of the bosses 15 is of generally ovoid plan, having a relatively large end 16 and a relatively small end 17. One side of each boss, designated by the reference numeral 18, is relatively straight, while the opposite side, designated by the reference numeral 19, is relatively curved. The maximum width of each boss is approximately half or slightly less than half the maximum length. The end edges 16 and 17 and the side edges 18 and 19 join each other smoothly. As will be clear from Figs. 5 and 6, the upper surfaces of the bosses 15 are smoothly and convexly curved.

The bosses 15 are of such a size and are so spaced that several of them will necessarily be engaged by each foot of an individual standing 25 on the tub-bottom. While the size of the bosses may vary considerably, I prefer to make each boss with a maximum length of approximately 1½ inches, a width of approximately ¾ inch, and a height above the tub-bottom of approximately 30 ½ inch. Smaller bosses tend to result in discomfort if made adequate in height to provide an effective non-skid surface, and materially larger bosses are relatively ineffective to prevent slipping.

35 The bosses 15 are desirably arranged on the tub-bottom in the manner indicated in Fig. 4, from which it will be apparent that the bosses are disposed in rows (indicated by the chain lines A) extending generally parallel to the longitudinal center-line of the tub and in transverse rows (indicated by the chain lines B) coinciding approximately with the contour lines of the tub-bottom. In the preferred arrangement, the bosses also form diagonal rows (indicated by the chain 40 lines C) extending at an angle of approximately 45° to the longitudinal center-line of the tub-bottom.

On each side of the longitudinal center-line of the tub-bottom, the bosses 15 are desirably of 50 substantially the same shape and are similarly oriented. Thus, as shown in Fig. 4, the major axis of each boss is disposed at an angle of approximately 45° with the longitudinal center-line of the tub, and the larger ends 16 and curved 55 sides 19 are directed generally toward the waste.

opening 12. The spacing of the bosses from each other, along the lines A, B, and C, approximates the length of the major axis of each boss.

I have found that bosses of the size, shape, and spacing above set forth do not result in any discomfort to the user of the tub and are very effective in preventing accidental slipping. I have found further that the above described shape and orientation of each individual boss and the above described arrangement of the bosses in longitudinal lines A and in transverse rows B, the latter approximately coinciding with contour lines, promotes free drainage of water from the tub-bottom to the waste-opening 12 when the tub is emptied.

I claim as my invention:

1. In a non-skid surface for the sloping bottom of a bath tub, the floor of a shower bath, or the like, a multiplicity of spaced ovoid bosses having upwardly presented convex surfaces, said bosses being oriented with their larger ends lower on the sloping surface than their smaller ends.

2. The invention set forth in claim 1 with the addition that said bosses are oriented obliquely with respect to the slope of the sloping surface, the higher side edge of each boss being materially straighter than the lower side edge, said bosses being arranged in transverse rows extending generally along contour lines of the sloping surface.

30

3. The invention set forth in claim 1 with the addition that said bosses are oriented obliquely with respect to the slope of the sloping surface, the higher side edge of each boss being materially straighter than the lower side edge.

4. The invention set forth in claim 1 with the addition that said bosses are arranged in transverse rows extending generally along contour lines of the sloping surface.

5. The invention set forth in claim 1 with the addition that the length of each boss is at least twice its width, the height of each boss being less than one-half its width.

6. The invention set forth in claim 1 with the addition that the length of each boss is at least twice its width.

ALBERT C. SANDBERG.
